UNITED STATES PATENT OFFICE.

LUDGER ELIEZER BRIE, OF SOUTH BEND, INDIANA, ASSIGNOR TO BENDIX BRAKE COMPANY, OF CHICAGO, ILLINOIS, A CORPORATION OF ILLINOIS.

BRAKE.

Application filed May 22, 1926. Serial No. 110,833.

This invention relates to brakes, and is illustrated as embodied in an internal expanding brake having novel shoes, preferably of pressed sheet metal.

5 An object of the invention is to provide a strong shoe, suitable for large brakes, with double-thickness stiffening webs spaced from each other and spaced inwardly from the side edges of the shoe. In one desirable arrangement there is a channel-section member, the bottom of the channel being cylindrical and forming part of the friction face and the sides or flanges of the channel forming parts of the stiffening webs, together with one or a pair of stampings or the like, each having a flange secured to one of the side flanges of the channel.

The above and other objects and features of the invention, including a novel pivot mounting and other desirable particular constructions, will be apparent from the following description of one illustrative embodiment shown in the accompanying drawing, in which:

25 Figure 1 is a vertical section through the assembled brake, just inside the head of the drum, showing the shoes in side elevation;

Figure 2 is a section through one end shoe, on the line 2—2 of Figure 1;

30 Figure 3 is a section through the center shoe on the line 3—3 of Figure 1;

Figure 4 is a partial section on the line 4—4 of Figure 1, showing the connection between two of the shoes; and

35 Figure 5 is a section on the line 5—5 of Figure 1, showing the anchored ends of the shoes.

The brake selected for illustration includes a drum 10, closed if desired at its open side by a suitable backing plate 12, and within which are arranged three shoes 14, 16, and 18. Shoe 16 is anchored on a pin 20 carried by the backing plate 12 and passing through a relatively large opening 22 in the stiffening web of shoe 14. Shoes 14 and 18 are connected at their ends to shoe 16 by pivots 24 and 26.

40 Shoes 14 and 18 are spread apart to apply the brake, against the resistance of a return spring 28, by means such as a double cam 30, and shoe 18 (with some assistance from shoe 14) acts against the resistance of an auxiliary return spring 32 to force shoe 16 against the drum. Normally spring 32 holds 45 shoe 16 in an idle position determined by

an adjustable eccentric stop 36 engaging and interlocking with one end of pivot 24.

According to an important feature of the invention, one shoe, preferably shoe 16, is built up from a channel-section stamping 38, and two side stampings 40 and 42. Each of the side stampings has a flange secured to one side flange of stamping 38 to form therewith a double-thickness stiffening web for the shoe. The outer cylindrical flanges of stampings 40 and 42 cooperate with the cylindrical bottom portion of the channel-section stamping, to form the friction face of the shoe, to which is secured the lining 44.

At the points embracing pivots 24 and 26, and the pivot or anchor 20, the flanges of stampings 40 and 42 are drawn outwardly to form tubular bosses 46 embracing the pivots, and cooperating with openings in the side flanges of stamping 38 to form spaced bearing surfaces engaging the pivot. This leaves the inner faces of the two shoe-stiffening webs substantially plane.

Shoes 14 and 18, which may be of the same construction and interchangeable, are 50 preferably built up of two stampings arranged back to back as shown in Figure 2. At the pivoted end of each shoe, the two flanges forming the central stiffening web are shown drawn out to form oppositely-projecting tubular bosses 48 forming spaced bearings embracing the pivot pin 24 or 26, and also serving as spacers confined between the inner plane surfaces of the two stiffening webs of shoe 16, and thus positioning 55 the end shoes laterally.

While one illustrative embodiment has been described in detail, it is not my intention to limit the scope of the invention to that particular embodiment, or otherwise than by the terms of the appended claims.

I claim:

1. A brake shoe comprising, in combination, a central channel-shaped part having a cylindrical portion forming part of the friction face of the shoe and two side flanges forming stiffening webs, and two parts, each having a flange secured to one of the side flanges of the channel-shaped part and a cylindrical portion flush with the cylindrical portion of the channel-shaped part and forming part of said friction face.

2. A brake shoe comprising, in combination, a channel-shaped part having a cylindrical portion forming part of the friction

face of the shoe and two side flanges forming stiffening webs, and another part having a flange secured to one of the side flanges of the channel-shaped part and a cylindrical portion flush with the cylindrical portion of the channel-shaped part and forming part of said friction face.

3. A brake shoe of pressed metal having a curved friction part and two stiffening webs integral with portions of the friction part and spaced apart from each other and spaced inwardly from the outer edges of the shoe.

4. A brake shoe of pressed metal having a cylindrical portion, and two double-thickness stiffening webs each formed of two flanges, each flange being integral with part of the cylindrical portion.

5. A brake shoe having at least at its end two spaced stiffening webs each consisting of two flanges secured together, one of each two flanges having an opening and the other being drawn out to form a tubular boss coaxial with respect to the opening, the opening and boss giving spaced bearing surfaces to be journaled on a pivot.

6. A brake shoe having at least at its end two spaced stiffening webs each consisting of two flanges secured together, one of each two flanges having an opening and the other being drawn out to form a tubular boss coaxial with respect to the opening, the opening and boss giving spaced bearing surfaces

to be journaled on a pivot, the bosses being on the outer sides of the webs and projecting away from each other, leaving the inner sides of the webs substantially plane.

7. A brake comprising two shoes and a pivot connecting them, one shoe having spaced webs each consisting of two flanges, each inner flange being substantially plane and having an opening embracing the pivot and each outer flange having an outwardly-projecting tubular boss embracing the pivot, and the other shoe having a central stiffening web consisting of two flanges each having an outwardly-projecting tubular boss embracing the pivot, the two last-mentioned bosses forming a spacer confined between the plane inner flanges of the first shoe.

8. A brake shoe of pressed metal having an outer segmental cylindrical part, and two stiffening webs spaced apart from each other and projecting beyond the end of the segmental part as spaced pivot arms, at least the projecting arms being built up of a plurality of flanges permanently fastened together.

9. A brake shoe of pressed metal having a curved friction part and two double-thickness stiffening webs spaced apart from each other and each built up of two separate flanges permanently secured together.

In testimony whereof, I have hereunto signed my name.

LUDGER ELIZÉ LA BRIE.
